VARIABLE DISPLACEMENT DRIVE

Wallace M. Cutler, Gloucester, Henry B. Greenough, Beverly, and Edwin S. Kant, Melrose, Mass., assignors to United Shoe Machinery Corporation, Flemington, N. J., a corporation of New Jersey

Application December 17, 1948, Serial No. 65,867

13 Claims. (Cl. 74—571)

1

This invention relates to mechanism for transmitting power and is illustrated as embodied in dynamically balanced variable displacement drives for operating nail drivers of a heel attaching machine and for vibrating a nail distributor which serves said machine. The nail distributor is fully disclosed in an application for United States Letters Patent Serial No. 65,868 filed December 17, 1948, in the names of Wallace M. Cutler et al.

The present invention consists in the novel features hereinafter described, reference being had to the accompanying drawings which illustrate embodiments of the invention selected for the purpose of illustration, the invention being fully disclosed in the following description and claims.

In the accompanying drawings,

Fig. 1 is a side view of a portion of the above-mentioned nail distributor which is described in said application Serial No. 65,868 and in which the dynamically balanced variable displacement drive shown in detail in Figs. 2, 3 and 4 is incorporated;

Fig. 2 is a section, partly broken away, on line II—II of Fig. 1;

Fig. 3 is a section on line III—III of Fig. 2;

Fig. 3A is a diagram illustrating the paths of travel of the center of mass of an eccentric and an adjacent half of a connecting rod and the center of mass of a counterweight as the throw of the eccentric is varied from $\frac{3}{8}$ " to 0;

Fig. 4 is a section on line IV—IV of Fig. 2;

Fig. 5 is a front view of a dynamically balanced variable displacement drive for use in a heel attaching machine; and

Figs. 6 and 7 are sections on lines VI—VI and VII—VII of Fig. 5.

The invention is described with reference to an eccentric drive 20 (Figs. 1 and 2) for vibrating or oscillating a nail carrier 22 of a nail distributor 24 and also with reference to an eccentric drive 26 for operating nail driving mechanism (not shown) of a heel attaching machine. The nail distributor 24, including the eccentric drive 20 thereof, shown herein, is disclosed in detail in said application Serial No. 65,868.

Referring to the nail distributor illustrated in Figs. 1 to 4, the carrier 22 is mounted upon four leaf springs 28 (Fig. 1) (only one shown) supported by a base (not shown) bolted to the above-mentioned heel attaching machine, said carrier having mounted in it the eccentric drive 20 which is operatively connected by a connecting rod 30 or actuator to a heavy abutment or weight 32 (Fig. 1) secured by bolts 34 to the lower ends of 55 the machine.

2

a pair of flexible leaf springs 36 (only one shown). The upper ends of the flexible leaf springs 36 are secured by bolts 38 to the carrier 22, the carrier being adapted to vibrate approximately horizontally, that is, in a direction indicated by reference numeral 40, as the eccentric drive 20 is rotated to cause nails (not shown) to travel in succession down guides or raceways 42 of the carrier. It is to be noted that, since the raceways 42 are inclined at an angle of only about 5° to the horizontal, the direction of displacement of the carrier 22 is approximately lengthwise of the guides, the maximum displacement of the carrier being approximately $\frac{1}{8}$ ". As will be explained later, the displacement of the carrier 22 may be reduced from a maximum of $\frac{1}{8}$ " in accordance with the length and/or style of the nail to be accommodated.

It is desirable that the carrier 22 move substantially horizontally only since displacement in any other direction, especially vertically, seriously interferes with the steady flow of nails down the raceways 42. With this consideration in view the eccentric drive 20 for operating the connecting rod 30 is dynamically balanced, such balance being maintained automatically irrespective of the throw of the connecting rod, as will be explained later. In the illustrative construction the relative masses of the abutment 32 and the carrier 22 are such that during operation of the drive 20 the abutment has a displacement three times that of the carrier.

The drive 20 comprises interfitting shafts 44 (Figs. 1, 2 and 3), 46 (Fig. 2) which are mounted for rotation in ball bearings 48, 50, respectively, mounted in the carrier 22. The shafts 44, 46 have eccentric portions 52, 54, the eccentric portion 52 having recesses 56 in which fit tongues 58 of the eccentric portions 54. Arranged at a side of the shaft opposite the eccentric portions 52, 54 and longitudinally offset from said portions are eccentric portions 60 (Figs. 2 and 4), 62 (Fig. 2) which balance the combined eccentric portions 52, 54. The eccentric portions 60, 62 may be described as being longitudinally offset at opposite ends of the eccentric portions 52, 54 and as being offset 180° circumferentially about the eccentric portions 52, 54. It will thus be apparent that the shafts 44, 46, including their eccentric portions 52, 60 and 54, 62, respectively, form in effect a single shaft which may be referred to as a driver and which is dynamically balanced. By forming separate shafts 44, 46 it is possible quickly and effectively to assemble the shafts in

Mounted for angular adjustment upon the eccentric portions 52, 54, which are in effect a single eccentric portion and will be referred to as such, is an eccentric or eccentric sleeve or member 64 (Figs. 2 and 3) which has secured to it inner races 66 of a ball bearing 68, outer races 70 of said bearing being secured to the connecting rod 30. The ball bearing 68, together with its inner and outer races 66, 70, form in effect, and will be considered, part of the connecting rod 30.

In order dynamically to balance the eccentric 64 and the adjacent half of the connecting rod 30, including its bearing 68, upon the drive shaft 44, 46, there are mounted upon the eccentric portions 60, 62 of said shaft counterweights 72 (Figs. 2 and 4) which may be described as ring shaped. To vary the throw of the connecting rod 30 and accordingly the amount of horizontal displacement of the carrier 22, the eccentric 64 is initially adjusted upon the eccentric portions 52, 54 of the shaft 44, 46 which are centered about a line 74 (Figs. 3 and 3A) parallel to and spaced from an axis of rotation 76 of the shaft 44, 46.

When the eccentric 64 has been angularly adjusted about the center line 74 of the eccentric portions 52, 54 to its position shown in Fig. 3, the connecting rod 30 has its maximum throw of about $\frac{1}{8}$ of an inch, said center line 74 being parallel to and arranged midway between a center line 78 of the eccentric 64 and the axis 76 of the shaft 44, 46, the center lines 74, 78 and the axis 76 lying in a common plane. The eccentric 64 is so constructed and arranged that its center of mass is located on the axis 78 which is equidistant from all points on the periphery of the eccentric 64 upon which the inner races 66 of the ball bearings 68 are mounted. It will thus be clear that when the eccentric 64 is rotated clockwise 180° from its position shown in Fig. 3 upon the eccentric portions 52, 54 the locus or path of the center of mass of the eccentric 64 and the adjacent half of the connecting rod 30 on the center line 78 is a semicircle 79 terminating at the axis 76. When the center line 78 coincides with the axis 76 the connecting rod has no throw.

The shaft 44, 46 is rotated by a pulley 80 (Fig. 2), an inner part 82 of which is secured to the shaft. Formed in the inner part 82 of the pulley 80 are bores 84 for receiving pins 86 secured to an outer part 88 of the pulley which is slidable upon a boss 90 of said inner part, a nut 92 being threaded onto a split tapered extension 94 of said boss. Interposed between the nut 92 and the outer part 88 of the pulley 80 is a spring 96 which serves to urge the outer part 88 of the pulley toward said inner part 82, thereby rendering effective a V-shaped belt 98 which drives the pulley. The belt 98 is driven by a pulley (not shown) which is rotatably mounted directly below the pulley 80 upon a base (not shown) of the distributor, the horizontal displacement of the carrier 22 with relation to its base having no appreciable effect on the driving effort of the belt.

In order to adjust the eccentric 64 into different angular positions upon the eccentric portions 52, 54 of the shafts 44, 46, said shafts are provided with bores 100, 102 (Fig. 2) in which fits a rod 104 against which the split tapered extension 94 of the inner part 82 of the pulley 80 is forced. Secured in transverse bores 106 of the rod 104 and extending through arcuate slots 108 in the eccentric portions 52, 54 and into a bore 110 (Fig. 3) of the eccentric 64 are pins 112 which, when the rod 104 is rotated, effect rotation of the

eccentric 64 upon the eccentric portions 52, 54 of the shaft 44, 46. Such adjustment is effected by placing a wrench (not shown) in a transverse hole 114 (Fig. 2) at the outer end portion of the rod 104 and turning said wrench, and accordingly the rod, about the axis 76, while holding the inner part 82 of the pulley 80 stationary, the nut 92 being previously backed away on the split tapered extension 94 of said inner part of the pulley to release the rod from the pulley.

It will be apparent that adjustment of the eccentric 64 on the eccentric portions 52, 54 of the shaft 44, 46, unless compensated for, will disturb the balance of the shaft. Accordingly, there are secured in bores 116 (Figs. 2 and 4) of the rod 104, pins 118 which extend through arcuate slots 120 in the eccentric portions 60, 62 of the shaft 44, 46 and with a clearance of about seven thousandths of an inch into bores 122 of the counterweights 72, the arrangement being such that the counterweights are rotated upon their eccentric portions 60, 62 in response to the above-described rotation of the rod 104 with relation to the shaft 44, 46.

When the eccentric 64 is positioned as illustrated in Fig. 3 the counterweights 72, which may be considered collectively as a two-part counterweight and will be referred to as such, are positioned upon their associated eccentric portions 60, 62 as shown in Fig. 4. When the parts are thus positioned a center line 124 through the eccentric portions 60, 62 of the shaft 44, 46 lies in a plane which includes the axis 76 and the center lines 78 and 74 and is also parallel to said axis, and is positioned the same distance at one side of said axis as the center line 74 is positioned at the opposite side of said axis.

The two-part counterweight 72 has a mass equal to that of the eccentric 64 plus the mass of an adjacent half of the connecting rod, including its bearing, said counterweight being so constructed and arranged that its center of mass lies in a line 126 which is parallel to, and lies in a plane which includes, the axis 76 and the center lines 78, 74 and 124, the center lines 78 and 126 being equally spaced at opposite sides of the axis 76. The center of mass of the two-part counterweight 72 also lies in a plane which is disposed at right angles to the axis 76 and includes the center of mass of the eccentric 64 and its adjacent half of the connecting rod 30. It will, therefore, be clear that if the counterweights 72 are rotated clockwise on their respective eccentricities 60, 62 from their positions illustrated in Fig. 4, the locus or path of a center of mass of the counterweights is a semicircle 128 the inner end of which coincides with the axis 76. When a line 130 indicating an angle alpha of adjustment of the eccentric 64 and the two-part counterweight 72 about their respective eccentric portions is drawn through the axis 76 intersecting the semicircles 79 and 128 which represent the loci of the centers of unbalanced mass of the eccentric 64 and an adjacent half of its connecting rod on the one hand and the two-part counterweight on the other hand, said centers of mass are equidistant from the axis 76 irrespective of the angle of adjustment, and since the masses are equal, the two unbalanced masses will counterbalance each other, thereby insuring that the eccentric drive 28 is at all times balanced. It will be noted that the angles alpha are twice as great as the angles beta which indicate the angular distances through which centers of mass

of the eccentric and the counterbalance swing with relation to the axis 152 of the driver.

In the above-mentioned heel attaching machine nail drivers (not shown) are raised in a nailing die (not shown) of the machine by a driver head (not shown) reciprocated by a connecting rod or actuator 150 (Figs. 5, 6 and 7) the throw of which may be varied in accordance with the lengths of nails to be driven into the work.

Mounted for rotation about an axis 152 in bearings 154 of a main frame 155 of the machine is a drive shaft 156 having formed integral with it a flange 158 to which a main casting 160 of a fly wheel 162 is secured by a plurality of bolts 164, 164A and 164B. The main casting 160 of the fly wheel 162 is positioned upon the flange 158 by dowels 166 which are permanently secured to the flange and pass through bores 168 of said casting. After positioning the fly wheel 162 upon the flange 158 and moving to its desired adjusted position a crank pin 170 forming part of a crank 172 to effect the desired throw of the connecting rod 150, the bolts 164A, 164B which pass through bores 174 (Fig. 6) in the main casting 160 of the fly wheel 162 and are threaded into the flange 158, are tightened to secure together the main casting and the various parts which, as will be hereinafter explained, are secured to the main casting and form together with said casting the fly wheel.

As above stated, it is desirable to vary the throw of the connecting rod 150 which is mounted upon a projecting portion 151 of the crank pin 170 of the crank 172, said crank fitting rotatably in a cylindrical recess or bore 176 (Figs. 5 and 6) formed in the main casting 160 of the fly wheel 162, an axis 178 of the bore and a disk portion 180 of the crank being parallel to the axis of rotation 152 of the shaft 156 and being offset one-half of an inch from, and below, said axis 152. The crank pin 170 which has a shank portion fitting in a cylindrical bore 182 (Fig. 6) of the disk portion 180 of the eccentric member 172 is secured to said disk portion by a pair of screws 184 which are threaded into diagonally disposed recesses 186 of said disk portion and have their inner ends forced against a circular notch 188 formed in the shank portion of the crank pin. The crank pin 170 has formed in it a lubricant receiving recess 190 normally closed by a screw 192.

In order to reduce to a minimum the vibration of the machine the fly wheel 162 is dynamically balanced to compensate for the mass of the projecting portion 151 of the crank pin and the mass of the lower half or a predetermined adjacent part of the connecting rod 150. The projecting portion 151 of the crank functions as an eccentric and may be referred to as such or as an eccentric member. It will be apparent that whenever the positions of the crank 172 and accordingly the crank pin 170 are changed to vary the throw of the connecting rod 150 and therefore the stroke of the nail drivers (not shown) of the machine, the balance of the fly wheel 162 and the shaft 156 upon which it is mounted is disturbed. Accordingly, there is provided an eccentric ring or counterweight 194 which is operatively connected for purposes of adjustment to the crank 172, the ring being rotated into different adjusted positions in an annular recess or bore 196 of the fly wheel casting 160 in timed relation with the angular adjustment of the eccentric member 151 and at all times balancing the crank pin 170 and the lower half of the connecting rod 150. The

annular recess 196 and accordingly the ring 194 are centered about an axis 198 which is parallel to, and is located one-half inch above, the axis of rotation 152 of the shaft 156. In order to insure that the fly wheel with the exception of the projecting portion 151 of its crank pin 170 is dynamically balanced, the main casting of the fly wheel is bored at selected localities.

The outer periphery of the disk portion 180 of the eccentric 172 and the inner periphery of the eccentric ring have teeth 200 and 202 formed on them and inserted in a two-well recess 204 in the main casting 160 of the fly wheel 162 are gears 206, 208 mounted upon a shaft 210 rotatable in a bore 212 (Fig. 7) of said casting. Also rotatable in a recess 214 (Fig. 5) of the main casting 160 of the fly wheel is a gear 216 secured to a shaft 218 rotatable in a bore (not shown) of said casting. The teeth 200 of the eccentric member 172 mesh 20 with the gear 216 which drives, through the gear 206, the shaft 210, and the gear 208 the eccentric ring 194, the construction and arrangement being such that the crank 172 and the ring 194 move degree for degree about their respective axes 178, 198. The fly wheel casting 160 in the vicinity of the gears is provided with a recess 220 and normally filling such recess is a cover plate 222 secured by screws 224 to the main casting, said plate having formed in it an opening 226 for receiving a wrench (not shown) which is inserted in a hexagonal socket 228 at the forward end of the pin 210.

Washers 230, 230A are interposed between heads of the screws 164A, 164B and the main casting 160 of the fly wheel 162, said washers 230 bearing against a step face 232 of the disk portion 180 of the crank 172 and the washers 230A bearing against the step face 234 of the eccentric ring 194. Preparatory to rotating the crank 172 and the eccentric ring 194 into their desired operating positions in the main casting 160 of the fly wheel 162 the screws 164A, 164B are loosened, the screw 164 remaining fastened. A wrench is then inserted in the hexagonal socket 228 in the shaft 210 and turned the proper amount to rotate the crank pin 170 into the proper position to effect the desired throw of the connecting rod 150. When the proper adjustment of the crank 172 has been effected the screws 164A, 164B are tightened, causing the washers 230, 232 to bear with clamping pressure against the step faces 232, 234 to hold the crank 172 and the eccentric ring 194 in their proper adjusted positions.

The eccentric ring 194 has removed from its peripheral portion a mass of material, providing a peripheral recess 236 which irrespective of the adjustment of the crank 172, is centered in radial alinement with an axis 238 of the crank pin 170 of the crank as shown in Fig. 5, a radial plane including the axis of rotation 152 of the shaft 156 and the axis 238 of said pin dividing the recess 236 in halves.

The eccentric ring 194 is so constructed and arranged that its mass is substantially equal to the mass of the axially offset or projecting portion 151 of the crank pin 170 plus the mass of the lower half of the connecting rod 150, a center of mass of the ring 194 lying in a line 240 which is parallel to the axis 152 and is displaced 180° from and is parallel to the crank pin axis 238.

In Fig. 5 the crank 172 is shown as arranged for the greatest throw of the connecting rod 150, that is, four inches, the axis 238 of the crank pin 170 being two inches below the axis of rotation

152. The locus or path of a center of mass, which lies on the axis 238 of the crank pin 170, as the crank 172 is adjusted from its setting for the greatest throw of the connecting rod 150 to its setting for the smallest throw of said rod, that is two inches, is a semicircle 242.

The axis 238 of the crank pin 170 and the line 240 in which the center of mass of the eccentric ring 194 lies, lie in a common plane, are parallel to each other and are equidistant from the axis 152 at opposite sides thereof. As above explained, the axes 178 and 198 about which the crank 172 and the eccentric ring 194 are adjusted are parallel to each other, lie in the plane just referred to and are spaced one-half inch from the axis 152, at opposite sides thereof.

A locus or path of a center of mass of the ring 194 during its adjustment from maximum to minimum throw of the crank 172 is a semicircle 246. It will thus be clear that any line drawn through the axis of rotation 152 of the shaft 156 and intersecting the circles 242, 246 will be bisected by the axis 152. Since the centers of mass of the crank pin 170 and the adjacent half of the connecting rod 150 on the one hand and the counterweight 194 on the other hand are displaced 180° from each other or are positioned diametrically opposite each other about the axis 152 of the shaft 156 and have moment arms which are at all times equal, it will be apparent that the shaft will at all times be balanced about its axis. It will be noted that the center of mass of the counterweight 194 is offset slightly longitudinally of the shaft 156 from the center of mass of the crank pin 170 and the adjacent half of the connecting rod 150. However, such slight longitudinal displacement of said centers of mass does not impair for any practical purpose the dynamic balance of the shaft 156. Since moment arms of the equal masses are equal and offset 180° about the axis 152 the shaft is dynamically balanced.

Having thus described the invention, what we claim as new and desire to secure by Letters Patent of the United States is:

1. In a variable speed drive, a balanced driver rotatable about and balanced with reference to an axis, an eccentric member and a counterweight which are bodily rotatable about said axis with the driver and have their centers of mass arranged at opposite sides of and at equal distances from said axis and in a common plane including said axis, an actuator which is carried by the eccentric member, the masses of the counterweight on the one hand and the eccentric member plus a predetermined adjacent portion of the actuator on the other hand being equal, and means for initially angularly adjusting the centers of mass of said eccentric member and said counterweight degree for degree in the same direction about said axis in circular paths which are of equal radius and the centers of which are equally spaced from and are arranged at opposite sides of the axis of the driver to retain the drive balanced irrespective of the throw of the eccentric member and accordingly the displacement of the actuator.

2. In a variable displacement drive, a frame, a drive shaft which is mounted in said frame and has an eccentric portion, an eccentric sleeve mounted upon said eccentric portion of the shaft, a connecting rod mounted upon said sleeve, said shaft having a pair of eccentric portions which are offset longitudinally at opposite ends respectively of the first-named eccentric portion and each of which is of the same size as, and is offset

180° circumferentially of the shaft from, an adjacent half of the first-named eccentric portion, counterweights mounted upon said pair of eccentric portions, means for adjusting the eccentric sleeve into different operative positions circumferentially on the first-named eccentric portion of the shaft to vary the throw of the connecting rod, and mechanism responsive to movement of said means for rotating the counterweights into different adjusted positions about the pair of eccentric portions of the shaft upon which they are mounted in order dynamically to balance the drive shaft irrespective of the position of the sleeve upon the first-named eccentric portion and accordingly the throw of the connecting rod.

3. In a variable displacement drive, a balanced driver rotatable about an axis, an eccentric member which is mounted for bodily rotation with the driver and has a cylindrical surface in the axis of which lies the center of mass of the eccentric member, an actuator mounted upon said cylindrical surface and having a displacement determined by the throw of the eccentric member, a counterweight mounted for bodily rotation with the driver, the centers of mass of the eccentric member and the counterweight being arranged at opposite sides of the axis of rotation of the driver in a plane which includes the axis of rotation of the driver, the mass of the eccentric member plus the mass of a predetermined adjacent part of the actuator times the distance from the axis of the driver to the axis in which said center of mass of the eccentric lies being substantially equal to the mass of the counterweight times the distance of the center of mass of said counterweight from the axis of rotation of the driver, means for angularly adjusting the eccentric member and the counterweight with relation to said driver about axes, respectively, which are parallel to the axis of rotation of the driver and are arranged at diametrically opposite sides of the axis of the driver to maintain the eccentric member and actuator forces acting thereon, on the one hand, and the counterweight, on the other hand, in their above-mentioned balanced relation irrespective of the setting of the eccentric member and accordingly of the actuator, and means for securing the eccentric member and the counterweight for bodily movement with the driver and for releasing the eccentric member and counterweight for angular adjustment upon the driver about their respective axes.

4. In a variable displacement drive, a balanced driver rotatable about an axis, an eccentric member which is mounted for initial angular adjustment upon said driver and is bodily rotatable with the driver, said eccentric being initially adjustable into different angular positions upon the driver about an axis parallel to and spaced from the axis of the driver to vary the throw of the eccentric member, a counterweight which is bodily rotatable with the driver and is mounted for initial angular adjustment upon the driver about an axis which is parallel to and is spaced from the axis of the driver and which is offset 180° about the driver axis from the axis about which the eccentric member is adjusted, mechanism for securing the eccentric member and the counterweight for bodily movement with the driver and for releasing the eccentric member and the counterweight for said initial angular adjustment upon the driver, and means for simultaneously moving the eccentric member and the

counterweight degree for degree about the axis of rotation of the driver with their centers of mass moving equal distances in opposite directions radially of the axis of said driver.

5. In a variable displacement drive, a driver rotatable and balanced about an axis, an eccentric member which is bodily rotatable with the driver and is initially adjustable on the driver into different operative positions about an axis which is parallel to and is spaced from the axis of rotation of the driver, a counterweight which is bodily rotatable with the driver and is initially adjustable into different operative positions on the driver about an axis which is parallel to, and lies in a plane including, the axis of rotation of the driver and the axis about which the eccentric member is adjusted, the axes about which the eccentric member and the counterweight are adjusted on the driver being positioned equal distances at diametrically opposite sides of the axis of the driver, and means for initially adjusting the eccentric member and the counterweight degree for degree in the same direction about their respective axes and accordingly about the axis of the driver and for simultaneously therewith moving the centers of mass of the eccentric member and the counterweight which centers are diametrically arranged at equal distances at opposite sides of the axis of the driver equal distances toward or away from the axis of the driver.

6. In a variable displacement drive, a driver rotatable about an axis, an eccentric member which is rotatable with said driver and is adjustable into different operative positions with relation to said driver about an axis which is parallel to and is offset at one side of the axis of rotation of said driver, a connecting rod, said eccentric member having a cylindrical periphery upon which the connecting rod is mounted and which is centered about an axis arranged parallel to the axis of rotation of said driver the axis of said cylindrical periphery including a center of mass of the eccentric member, a ring-shaped counterweight which is rotatable with the driver and is adjustable into different operative positions on the driver about an axis which is parallel to and lies in a plane including the axis of rotation of the driver and the axis about which the eccentric member is adjusted, the axes about which the eccentric member and the counterweight are adjusted relatively to said driver being positioned at equal distances at opposite sides of the axis of rotation of the said driver, said counterweight having a mass which is equal to the mass of the eccentric member plus the mass of an adjacent half of the connecting rod and which is offset 180° about the axis of rotation of said driver from the axis of the periphery of the eccentric member and has its center of mass located the same distance from the axis of rotation of the driver that the axis of the periphery of the eccentric member is located from the axis of rotation of the driver, and means for simultaneously adjusting the eccentric member and the counterweight, degree for degree, in the same direction about their respective axes of adjustment to insure that the driver shall be balanced irrespective of the adjustment and accordingly the throw of the eccentric member.

7. In a variable displacement drive, a powered shaft rotatable about an axis, a fly wheel secured to the shaft, a member rotatable with the fly wheel and adjustable into different operative positions with relation to the fly wheel about an axis which is parallel to and is offset at one

side of the axis of rotation of the shaft, a crank pin which is secured to said member and has an axis, a connecting rod mounted upon said crank pin, and a counterweight which is rotatable with the fly wheel and is initially adjustable with relation to said fly wheel about an axis which is parallel to the axis of rotation of the shaft, is arranged in a plane including said other two axes and is offset laterally from the axis of rotation of the shaft at a side of the shaft axis opposite the axis about which said member is adjustable, the axes about which the crank pin and the counterweight are adjustable relatively to the fly wheel being positioned at equal distances from the axis of rotation of the shaft, said counterweight having a mass which is equal to the combined masses of the crank pin and an adjacent half of the connecting rod, the center of mass of the counterweight and the axis of the crank pin being positioned the same distance from the axis of rotation of the shaft and being offset 180° circumferentially of said shaft from one another.

8. In a variable displacement drive, a driven shaft rotatable about an axis, a fly wheel secured to the shaft, an eccentric member rotatable with the fly wheel and initially movable into different adjusted positions upon the fly wheel about an axis which is parallel to the axis of rotation of the shaft and is offset at one side thereof, said eccentric member comprising a crank pin, a connecting rod mounted upon the crank pin, and a ring-shaped counterweight which is rotatable with the fly wheel and is initially movable into different adjusted positions in the fly wheel about an axis which is parallel to the axis of rotation of the shaft, is arranged substantially in a plane including the other two axes and is offset 180° about the axis of rotation of the shaft from the axis of rotation of the eccentric member, the axes about which the crank pin and the counterweight are adjusted relatively to the fly wheel being positioned at equal distances from the axis of rotation of the shaft.

9. In a variable displacement drive, a powered shaft rotatable about an axis, a fly wheel secured to the shaft and having a cylindrical bore the axis of which extends parallel to and is offset at one side of the axis of rotation of the shaft, a crank mounted for angular adjustment in said bore, said fly wheel having an annular bore centered about an axis which is parallel to the axis of rotation of the shaft and offset 180° from the axis of the cylindrical bore about the axis of rotation of the shaft, the axes of the cylindrical and the annular bores being spaced the same distance from the axis of rotation of the shaft, a counterweight mounted for angular adjustment in the annular bore, means for securing the crank and counterweight in their bores to the fly wheel and for releasing the crank and the counterweight for adjustment in their bores with relation to the fly wheel, means for moving the crank into different angularly adjusted positions in the cylindrical bore of the fly wheel, and mechanism responsive to movement of the last-named means for angularly adjusting the counterweight in its annular bore to insure that the fly wheel is balanced for all adjustments of the crank.

10. In a variable displacement drive, mechanism comprising drive shafts rotatable about a common axis and having eccentric portions which interfit longitudinally of said axis to cause said shafts to rotate as a unit, an eccentric sleeve mounted upon the eccentric portions, a connecting rod mounted upon said sleeve, and means for

moving the sleeve into different adjusted positions circumferentially of said eccentric portions to vary the eccentricity of the sleeve and accordingly the throw of the connecting rod.

11. In a variable displacement drive, bearings, a hollow shaft which is rotatable in said bearings about an axis and has an eccentric portion provided with an arcuate slot, means for rotating the shaft, an eccentric sleeve mounted for adjustment upon the eccentric portion of the shaft, a member which extends into said hollow shaft and is constructed and arranged to be secured to said shaft for rotation therewith or to be released from said shaft for angular adjustment about said axis with relation to the shaft, a pin which is slidable along the arcuate slot of the eccentric portion of the shaft and is operatively connected to said member and to said eccentric sleeve for varying the operative position of the eccentric sleeve upon the eccentric portion of the shaft and accordingly the eccentricity of the sleeve in response to the angular movement of said member about said axis in said shaft.

12. In a variable displacement drive, bearings, a hollow shaft which is rotatable in said bearings about an axis and has an eccentric portion provided with an arcuate slot, means for rotating the shaft, an eccentric sleeve mounted for adjustment upon the eccentric portion of the shaft, a member which extends into said hollow shaft and is constructed and arranged to be secured to said shaft for rotation therewith or to be released from said shaft for angular adjustment with relation to the shaft about said axis, said shaft having a pair of eccentric portions which are provided with arcuate slots and which are longitudinally offset from the first-named eccentric portion at opposite ends thereof and are also offset 180° circumferentially from said first-named eccentric portions, counterweights mounted for angular adjustment upon said pair of eccentric portions of the shaft, and pins which are slidable along said arcuate slots and are operatively connected to the sleeve and to the member on the one hand and to the counterweights and to the member on the other hand for simultaneously moving the sleeve and the counterweights into different angularly adjusted positions upon their associated eccentric portions.

13. In a variable displacement drive, a powered shaft rotatable about an axis, a driving eccentric

which is rotatable with the shaft and is initially adjustable into different operative positions with relation to the shaft about an axis which is parallel to and is offset at one side of the axis of rotation of the shaft, said eccentric having a cylindrical driving face centered about an axis arranged parallel to the axis of rotation of the shaft, the axis of said cylindrical driving face including a center of mass of the eccentric, a counterweight which is rotatable with the shaft and is initially adjustable into different operative positions with relation to the shaft about an axis which is parallel to and lies in a plane including the axis of rotation of the shaft and the axis about which the eccentric is adjusted, the axes about which the eccentric and the counterweight are adjusted relatively to the shaft being positioned at equal distances at opposite sides of the axis of rotation of the shaft, said counterweight having a mass which is equal to the combined mass of the eccentric and an adjacent half of the connecting rod and which is positioned diametrically at the opposite side of the axis of rotation of the shaft from the center of combined mass of the eccentric and an adjacent half of the connecting rod and at the same distance from the axis of rotation of the shaft as is positioned the axis of said cylindrical driving face of the eccentric and accordingly the center of combined mass of the eccentric and an adjacent half of the connecting rod, and means for initially adjusting the eccentric and the counterweight in timed relation about their respective axes to insure that the shaft shall be balanced irrespective of the throw of the eccentric.
